UNITED STATES PATENT OFFICE

100,459

DESIGN FOR A FLUID FUEL BURNING FIREPLACE

Lucien Sulzer, Chicago, Ill.

Application November 22, 1935, Serial No. 59,697

Term of patent 14 years

To all whom it may concern:

Be it known that I, Lucien Sulzer, a citizen of the United States of America, residing at 432 West Superior Street, Chicago, county of Cook and State of Illinois, have invented a new, original, and ornamental Design for a Fluid Fuel Burning Fireplace, of which the following is a specification, reference being had to the accompanying drawing, forming a part thereof.

Fig. 1 is a perspective view of a fluid fuel burn-

ing fireplace with transparent door, showing my new design. Fig. 2 is a detailed view thereof showing the imitation fuel through the transparent door.

Both ends of applicant's fluid fuel burning fireplace are the same.

I claim:

The ornamental design for a fluid fuel burning fireplace substantially as shown and described.

LUCIEN SULZER.
